UNITED STATES PATENT OFFICE.

CORLETT L. SCOTT, OF DENVER, COLORADO.

DESIGN FOR A FOUNTAIN-FAUCET.

47,475.

Specification for Design.

Patented June 15, 1915.

Application filed October 20, 1914. Serial No. 867,662. Term of patent 7 years.

To all whom it may concern:

Be it known that I, CORLETT L. SCOTT, a citizen of the United States, residing at Denver, in the county of Denver and State of Colorado, have invented a new, original, and ornamental Design for Fountain-Faucets, as shown in the accompanying drawing and described in the following specification.

The figure is a view in side elevation of a fountain faucet.

I claim:

The ornamental design for a fountain faucet as shown.

CORLETT L. SCOTT.

Witnesses:

CARLE WHITEHEAD,
ALBERT L. VOGL.
